(57) **CLAIM**

The ornamental design for a beverage container lid, as shown.

DESCRIPTION

FIG. 1 shows a top perspective view of a first embodiment of a beverage container lid, showing my new design.

FIG. 2 shows a front elevational view thereof;

FIG. 3 shows a rear elevational view thereof;

FIG. 4 shows a left side elevational view thereof;

FIG. 5 shows a right side elevational view thereof;

FIG. 6 shows a top plan view thereof;

FIG. 7 shows a bottom plan view thereof;

FIG. 8 shows a top perspective view of a second embodiment of a beverage container lid, showing my new design.

FIG. 9 shows a front elevational view thereof;

FIG. 10 shows a rear elevational view thereof;

FIG. 11 shows a left side elevational view thereof;

FIG. 12 shows a right side elevational view thereof;

FIG. 13 shows a top plan view thereof; and,

FIG. 14 shows a bottom plan view thereof.
